UNITED STATES PATENT OFFICE.

JOHN T. SMITH, OF OBERLIN, KANSAS, ASSIGNOR OF ONE-HALF TO JOHN A. QUINN, OF OBERLIN, KANSAS.

BELT-GUIDE.

1,079,031.

Specification of Letters Patent.

Patented Nov. 18, 1913.

Application filed October 31, 1910. Serial No. 589,946.

To all whom it may concern:

Be it known that I, JOHN T. SMITH, a citizen of the United States, residing at Oberlin, in the county of Decatur and State 5 of Kansas, have invented certain new and useful Improvements in Belt-Guides, of which the following is a specification, reference being had therein to the accompanying drawing.

10 The belt-guide provided by the invention is particularly adapted for use in connection with the drive-pulleys of traction or other engines employed to run threshing-machines, corn-shellers, and other machinery, in order to maintain the belt on the pulley while the engine and a machine are being lined up and to prevent the belt while 15 in operation from being run off the pulley under the influence of the wind or some 20 other cause.

It is an object of the invention to provide a belt-guide of this nature which may be easily swung out of operative position when it is desired to put on or take off a 25 belt and which may be just as easily returned to operative position.

When read in connection with the description herein, the details of construction and arrangement of parts contemplated by the 30 invention will be apparent from the accompanying drawings, forming part hereof, wherein an embodiment of the invention as applied to a traction-engine is disclosed, for purposes of illustration.

35 While the form of the invention shown in the drawings is preferred, it is to be understood that it is not the intention to be necessarily limited to the precise delineation herein in interpretation of the claim herein-after, as it is obvious that various changes 40 within the scope of the invention can be made in the structure shown and described.

Like reference-characters refer to corresponding parts in the several views of the 45 drawings, of which—

Figure 1 is a side view with the guide in operative position; Fig. 2 is an end view; Fig. 3 is a top view; and Fig. 4 is an enlarged sectional view of the lower guide.

50 Having more particular reference to the drawings, 6 designates the boiler of a traction-engine, and 7 the drive-pulley thereof located toward the front of the engine. A bracket 8 is supported by the boiler in the 55 rear of the pulley, and a shaft 9 is journaled

in this bracket and extended laterally therefrom so that a portion is in line with the pulley. Two arms 10 are extended radially from shaft 9 and then upwardly near their outer ends to form portions 11, and the 60 ends of these portions are joined by a connecting piece 12. A roller 13 is journaled on each arm 10 between abutments 14 near shaft 9, and a roller 15 is journaled on each upwardly-extending portion 11. The rollers 13 and 15 are so positioned on the arms that when these arms are swung downwardly by rocking of shaft 9 they will be in proper position to be engaged by the 65 edges of a belt on the pulley in the upper 70 run and in the rear arc of its contact with the pulley when the belt has a tendency to run off.

The shaft 9 has at one end an arm 16 connected by a link or rod 17 with a hand-lever 75 18 pivoted on a member 19 supported by the engine-boiler. The member 19 is located at the rear of the engine within easy reach of the engineer, and it includes a rack 20 with which a spring-controlled pawl 21 on the 80 lever coöperates to hold the latter in the various positions of adjustment. When it is desired to raise the rollers 13 and 15 out of the way on putting on or taking a belt off the pulley, the hand-lever is shoved forwardly and the shaft 9, through the instrumentality of the rod 17 and arm 16, rocked to raise the arms 10 which are then held in raised position by engagement of the pawl 85 with the rack. The rollers are lowered into 90 operative position by reversal of this movement. In order that the rollers may be stopped at exactly the right operative position with respect to the pulley, the member 95 19 has a stop 22 thereon with which the lever contacts when the rollers have reached this position, the further descent of the rollers and engagement of connecting piece 12 with the belt being thereby obviated.

In order to guide the lower run of the 100 belt, an upright roller 23, a horizontal roller 24, and a normally upright roller 25 are supported by a bracket 26 fixed to the side of the engine-boiler. The roller 23 is journaled between the laterally-extending portions 27 and 28 of the bracket. A shaft 29 is continued from the lower portion 28 of the bracket upon which roller 24 is journaled. A rocking member 30 is positioned on shaft 29 outside of roller 24 and this member car- 110

ries a shaft 31 upon which the roller 25 is journaled. Assuming the roller 25 is in its normal upright position to be engaged by the edge of the belt, an arm 32 depends from the member 30 and below shaft 29, and this arm has a rearward extension 33. A rod 34 connects extension 33 with an arm 35 fixed to the shaft 9. Arm 35 is so disposed on shaft 9 that when that shaft is rocked to swing the roller-carrying arms 10 upwardly to inoperative position, the member 30 will be rocked to swing roller 25 rearwardly and downwardly out of the way of a belt being placed on or taken off the pulley. The rearward extension 33 serves to permit the rod to give member 30 the amount of turn required to sufficiently lower the roller 25. When shaft 9 is rocked to swing the roller-carrying arms down to operative position, the roller 25 will be swung upwardly on its carrying member 30 to operative position. The arm 35 has a plurality of apertures 36 in any one of which the end of rod 34 may be engaged to give the member 30 greater or less rocking movement as desired.

Should it not be desired to depend entirely upon the stop 22 coöperating with the hand-lever 18 to limit the movement of the rollers to operative position, a chain or the

like 37 of the proper length may be connect- 30 ed to the piece 12 and to some relatively high fixed part of the engine, as for instance the awning-support 38.

Having thus described my invention, what I claim as new, and desire to secure by Letters Patent, is—

In combination with a belt-pulley, a guide for a belt thereon comprising a suitably supported rock-shaft, arms carrying guide-rollers swingable to and from positions on 40 each side of the pulley contiguous to the upper run of the belt and to the rear arc of contact of the belt with the pulley, a shaft below the pulley, a swingable member thereon, a normally upright roller journaled on 45 said member, and a connection between said rock-shaft and said swingable member whereby said normally upright roller will be swung from upright position on movement of said arms from positions contiguous 50 to the belt.

In testimony whereof I affix my signature in presence of two witnesses.

JOHN T. SMITH.
